[57] CLAIM

The ornamental design for a travel organizer, as shown and described.

DESCRIPTION

FIG. 1 is a front isometric view of a travel organizer with its front flap and one drawer opened, showing my new design; and,

FIG. 2 is a top plan view thereof, with the front flap opened and all drawers shut;

FIG. 3 is a top plan view thereof;

FIG. 4 is a front elevational view thereof, in which the front flap is shown in a closed position;

FIG. 5 is a left side elevational view, the right side being a mirror image thereof;

FIG. 6 is a top plan view thereof;

FIG. 7 is a rear elevational view thereof;

FIG. 8 is a bottom plan view thereof, in closed position.

FIG. 1

FIG. 2
